DESIGN FOR A STOCKING

Luther Earl Newton, Hickory, N. C.

Application May 7, 1941, Serial No. 100,830

Term of patent 3½ years

To all whom it may concern:

Be it known that Luther Earl Newton, a citizen of the United States of America and residing at Hickory, in the county of Catawba, State of North Carolina, has invented a new, original, and ornamental Design for a Stocking, of which the following is a specification, reference being had to the accompanying drawing, forming a part thereof.

The figure is an elevation of one side of the stocking showing my design, the other side of the stocking being identical to the side shown.

I claim:

The ornamental design for a stocking, substantially as shown and described.

LUTHER EARL NEWTON.
